UNITED STATES PATENT OFFICE.

FRANK HENRY FARRINGTON, OF BIRMINGHAM, ALABAMA.

LAP TABLE.

Application filed March 21, 1925. Serial No. 17,417.

This invention relates to a "lap table" and the object of my invention is to construct a simple adjustable folding table which may be adjusted to any angle supporting a book 5 or work in a convenient manner for use.

In the accompanying drawings:

Fig. 1 is a front view showing the table open for use.

Fig. 2 is a perspective view looking from 10 the rear.

Fig. 3 is a transverse sectional view through the table when folded.

Fig. 4 is a detail sectional view taken on line 4—4 of Fig. 3.

Fig. 5 is a perspective view of the table 15 folded, when not in use.

The numeral 1 indicates a base board. The numeral 2 indicates a top board or book 20 rest. The numerals 3—3 indicate links pivoted as at 4—4 to one edge of the base board and pivoted as at 5—5 to the opposite edge of the top board 2.

Interposed between the base board and the top board 2 are front and rear collapsible 25 frames. The rear frame consists of crossed members 6 and 7 pivoted together as at 8. The lower end of the member 7 is pivoted as at 9 to the base board, the opposite end thereof being pivoted as at 10 to the member 30 11, slidably received upon a track 12 secured to the underside of the top board. A thumb nut 13 provides a means for adjusting the member 11 horizontally along the track 12. The upper outer end of the member 6 is pivoted 35 as at 14 to the rear edge of the top board 2, while the lower opposite end is pivoted as at 15 to the sliding member 16, received upon a track 17 secured to the base board 1. A thumb nut 18 provides a means 40 for adjustably securing the member 16 to the track 17. The numerals 19 and 20 indicate two crossed members pivoted as at 21. These crossed members are arranged at the front end of the lap table, the member 20 45 being pivotally connected as at 22 to the base board and having its upper opposite end pivotally connected as at 23 to the sliding member 24, received upon a track 25 secured along the upper edge of the top board 2, and the thumb nut 26 provides the means 50 for adjustably securing the member 24 to the track 25. The upper end of the crossed member 19 is likewise pivoted as at 27 to the top board 2 having its lower end pivoted as at 28 to the sliding member 29, received 55 upon the track 30 secured to the outer edge

of the base 1. A thumb nut 31 provides means for adjustably securing the member 29 to the track 30.

When it is desirable to adjust the top board 2 relative to the base 1, the top board 2 is raised manually to the desired height and angle whereupon the thumb nuts 13, 18, 26, and 31 are tightened to hold the top board in the desired angle. The links 3—3 60 65 serve to eliminate any lateral movement of the board after being adjusted to the desired height and angle. As is obvious, any angle or height may be obtained within the range 70 of the links 3 by independent adjustment of the front and rear crossed supporting members.

The numeral 32 indicates dial pins which are removably received in openings 33 in the top board. When not in use, these dial pins 75 are adapted to be received in the block 34 arranged upon the base board.

It is obvious that more or less slight changes might be made as to the details of construction without departing from the 80 general scope of my invention, therefore, I do not wish to be limited to the exact structure as shown.

I claim:

1. A folding lap table comprising a base board and a top board, transverse links interposed between the base and top boards and pivotally connected to the opposite edges thereof, front and rear crossed members interposed between the base and top boards, the upper and lower ends of said front and rear crossed members being pivotally connected to the base and top boards on one side, tracks secured to the opposite side to the base board and top member, adjustable members adjustably secured to said tracks and pivotally secured to the opposite upper and lower ends of said crossed members whereby the horizontal movement of the said adjustable members will effect a vertical movement with said top board.

2. A folding lap table comprising a base-board and a top-board, transverse end links pivotally connected to the front of the base-board and the rear of the top-board whereby the rear of the top-board moves in an arc relative to the base-board, front and rear crossed members interposed between and longitudinally of the top and base-board, one set of the upper and lower ends of the crossed members being pivotally connected to the top and base-board, the opposite set 105 110

of the upper and lower ends being pivotally connected and horizontally adjustable relative to the top and base-board, whereby the top board may be adjusted vertically at an angle.

3. A portable lap table including base and top boards, independent pairs of crossed members interposed between the base and top boards, and pivotally connected therewith, means for permitting at least two of said crossed members to have slidable, pivotal and adjustable connection with at least one of the boards, and means permitting independent adjustment of the pairs of crossed members.

4. A portable lap table including base and top boards capable of being folded into close proximity to each other and approximately parallel, independent pairs of crossed members interposed between the base and top boards and pivotally connected therewith, the pairs of crossed members being disconnected from each other, and means for permitting at least two of said crossed members to have slidable, pivotal, and adjustable connection with at least one of the boards and in a plane approximately parallel therewith for angularly and vertically adjusting the top board upon the base board.

5. A portable lap table including base and top boards capable of being folded into close proximity to each other, independent pairs of crossed members interposed between the base and top boards and pivotally connected therewith approximately at the opposite edges, said pairs of crossed members being independent and disconnected from each other, and means permitting at least some of said crossed members to have slidable, pivotal and adjustable connection with at least one of the boards and in a plane approximately parallel therewith for angularly and vertically adjusting the top board upon the base board.

6. A table including boards with crossed members interposed therebetween and having a universal joint connection with each, said crossed members being collapsible between the boards, and adjustable means for said crossed members for permitting said boards to be adjusted relative to each other.

7. A table including top and base boards having crossed members interposed therebetween, a universal joint connection between at least some of said crossed members and the boards, and adjustable means for said crossed members for adjusting the top and base boards relative to each other.

8. A portable lap table including base and top boards, independent pairs of crossed members interposed between the base and top boards and pivotally connected therewith, means for permitting at least two of said crossed members to have slidable, pivotal and adjustable connection with at least one

of the boards for angularly and vertically adjusting the top and base boards relative to each other, and links extending approximately at right angles to the crossed members and pivotally connected with the boards for limiting relative movement therebetween.

9. A portable lap table including base and top boards, independent pairs of crossed members interposed between the base and top boards and pivotally connected therewith at points adjacent the edges thereof, and means for permitting at least two of said crossed members to have slidable, pivotal and adjustable connection with at least one of the boards, and for angularly adjusting an edge of the top board to which corresponding ends of any pair of links are connected in any plane parallel to the corresponding edge of the base board.

10. A portable lap table including base and top boards capable of being folded in close proximity to each other and approximately parallel, independent pairs of crossed members interposed between the base and top boards and pivotally connected therewith at points approximately adjacent the opposite edges thereof, and means for permitting at least two of said crossed members to have slidable, pivotal and adjustable connection with at least one of the boards and for angularly adjusting an edge of the top board to which corresponding ends of any pair of links are connected in any plane parallel to the corresponding edge of the base board.

11. A collapsible and reversible lap table comprising two relatively thin boards, each of which is designed for use as a table, independent crossed link units having relative movement at their crossing points, located between and connected with said boards, all of said connections being pivotal, and at least some of said connections being both pivotal and slidable on at least one of said boards, whereby, when one of said boards is used as a writing surface it will be closer to the body of the user than the opposite board used as a reading surface in reversed position.

12. A device of the character described, including two boards, confining members located therebetween, and having fixed pivotal connection with the opposite edges of said boards, whereby each pivotal point may become an independent center of adjustment or movement of the board, and adjusting means located between the two boards, and having universal joint connection therewith as well as adjustable connection, whereby to permit the rocking of the uppermost board to various lateral positions and inclinations, and the raising, lowering, and locking of said uppermost board.

In testimony whereof I affix my signature.
FRANK HENRY FARRINGTON.
